UNITED STATES PATENT OFFICE.

STEWART HARTSHORN, OF MILLBURN, NEW JERSEY.

DESIGN FOR A BRACKET FOR SHADE-ROLLERS.

SPECIFICATION forming part of Design No. 16,037, dated April 14, 1885.

Application filed January 14, 1885. Term of patent 14 years.

To all whom it may concern:

Be it known that I, STEWART HARTSHORN, a citizen of the United States, residing in Millburn, in the county of Essex and State of New Jersey, have invented and produced a new and original Design for a Bracket for Shade-Rollers, of which the following is a specification, reference being had to the accompanying drawings, forming a part thereof.

10 This design relates to window-brackets for shade-rollers; and the leading feature consists in a conventional representation of a door-key, such as is commonly used in the usual form of locks.

15 The door-key is represented as standing out from the plate and bearing on the outer end of its stem B the ward C, in which is the angular or round opening c, as is seen in Figures 1 and 2. Extending from the stem to the bottom of the part A is a brace, D, which may be either straight, as shown in Fig. 1, or curved, as in Fig. 2.

20 Ornamental scrolls or braces may extend

from the edge of the ward to the brace D, and from the latter to the part A; but these scrolls and braces may be omitted without changing the design of the bracket.

It will be evident that the shape of the particular key may vary slightly from that shown in the drawings, providing a sameness of appearance is maintained, without altering the nature of my design, the essential feature of which is the bracket substantially in the form of a key.

What I claim is—

The design for a bracket for a shade-roller herein shown and described, the same consisting of the conventional representation of a door-key having an angular or round opening, c, substantially as described.

Dated this 9th day of January, 1885.
